VARIABLE-LENGTH ANTENNA

Walter Berndt, Berlin, Germany, assignor to
Telefunken Gesellschaft für Drahtlose Tele-
graphie m. b. H., Berlin, Germany, a corpora-
tion of Germany

Application January 12, 1938, Serial No. 184,534
In Germany December 16, 1936

6 Claims. (Cl. 250—33)

It is known from the earlier art that antennae which are to operate within and cover a large wave-band must be constructed so that the length thereof may be altered. It is also known in the prior art that the antenna may be tuned by steady variation of the antenna length so that adaptation or matching, throughout the entire band or range, to an energy feeder lead or transmission line will be insured. In order that alteration in the length of the antenna may be effected mechanically the shifting means must be insulated for the radio frequency potential between ground and antenna or inner conductor of the feeder cable. Where large transmitter powers and the high potentials connected therewith are concerned, this problem is attended with serious technical difficulties from an insulation viewpoint.

The suggestion is therefore made according to this invention to leave the rod-shaped antenna conductor directly connected with the inner conductor of the concentric or co-axial feeder line itself unaltered, while instead the counterpoise which is connected with the end of the outer conductor of the energy transmission line is made capable of being shifted, with the result that the effective or active part of the antenna protruding from the outer conductor is varied in its length. This scheme has the advantage that such means as are used for alteration of the length, say, motors, air-pressure cylinders, or the like, are at ground potential and may operate without any insulating intermediary parts. Furthermore, also, such devices as are provided for the purpose of indicating the effective antenna length to which the aerial may have been adjusted at a remote point, will always be at ground potential so that they may be readily shielded against effects of the radio frequency potential. In this scheme, the counterpoise fulfills two important functions, to wit: it allows the distribution of the field of an antenna erected above an infinitely large conducting surface to be as uniform as feasible; and it prevents induction currents (and their harmful effects) from arising over the radiation field at the antenna end of the concentric or co-axial feeder or transmission line.

If the counterpoise were to be dispensed with, accurate matching with a relatively large wave-band would no longer be insurable.

An illustrative embodiment of the idea underlying the present invention is shown in the drawing Fig. 1. Fig. 2 shows a modification for a guyed antenna; Fig. 3 shows a mechanical arrangement for shifting the height of the counter-

poise; and Figs. 4 and 5 show a further modification of the invention in two different operative positions.

Referring to Fig. 1, A denotes the antenna, G is the shiftable counterpoise which consists of a disk with a piece of pipe attached thereto. The disk may consist of sheet-metal, wire mesh or wires or ribbons extending and fastened radially or star-fashion. The disk may be of any shape, but it is preferable that the top face of the disk should consist of a material possessing high electric conductivity.

In the embodiment shown in Fig. 2, the counterpoise G has notches which serve to accommodate the guy wires or cables P. It is thus feasible to shift the counterpoise to a point in close proximity to the points where the stay cables or wires are attached.

Fig. 3 shows the one means of causing the displacement or shifting of the counterpoise. Also in this figure, G denotes the counterpoise which is shiftable on the insulator piece I on the antenna A. K is a high-frequency cable with the terminal box or closure member E, the inner conductor thereof being connected with the antenna A. Current is fed from the cable to the counterpoise by way of the tubular or pipe piece S.

The tubular part of the counterpoise G jointly with the extension of the antenna constitutes the energy feeder whose characteristic impedance is governed by the ratio of the two diameters. Choosing the same diameter ratio as for cable K, then the cable is electrically extended as far as the antenna base. If the antenna has a length so that the base resistance is ohmic in nature (approximately $\lambda/4$, $\lambda/2$, $3/4\lambda$, etc. where (λ) denotes the operating wave length), and if the characteristic impedance of the cable is made equal to the resistance at the antenna base, it will be possible to obtain accurate matching within a wide wave-band. The size of this wave-band depends only upon the extent to which shifting of the counterpoise is mechanically feasible.

It is not possible in all cases to make the characteristic impedance of the cable equal to the resistance of the antenna base or terminal. For reasons of safety against shock, commercial radio frequency cables have a characteristic impedance of around 60 ohms. In such a case it is expedient to so choose the characteristic impedance of the pipe piece interposed between antenna and cable that it ranges between the value of the resistance at the antenna base and

the characteristic impedance of the cable. As a limit, the same could be made equal also to either of the said two resistance values. If the resistance of the antenna base and the characteristic impedance of the cable are not unduly discrepant, then fairly close matching throughout the whole wave-band will thus always be obtained.

If the antenna base resistance and the characteristic impedance of the cable differ widely, or if the occurrence of standing waves must be absolutely avoided for reasons of the cable potentials whenever extremely large transmitter powers are dealt with, the desired end condition may be obtained by the insertion of several pipe pieces of dissimilar characteristic impedance values between the antenna and the cable.

An exemplified embodiment of this idea is illustrated in Figs. 4 and 5. Referring to these figures, G again stands for the counterpoise disposed so as to be shiftable along the aerial A, the counterpoise being supported upon the insulator ring I and the current contact piece S. The embodiments Figs. 4 and 5 differ from each other only by the length of the shiftable counterpoise. The antenna itself and its extension consist of two pipes of different diameters. The length is made about equal to $\frac{1}{4}$ of the maximum working wave length. The counterpoise 30 is connected with two tubes which are also of dissimilar diameters; and its length is also approximately equal to one-fourth the maximum working wave length. It will thus be seen that between the antenna base point and the cable terminal box there are arranged three tubular pieces of different characteristic impedance, and all of them are caused to have their lengths altered as a result of a shift of the counterpoise. The top and the bottom pipe piece become greater in length when the counterpoise is raised, while the central pipe piece is shortened by exactly the same amount by which the length of the antenna is abbreviated. For instance, if the length of the antenna is $\lambda/4$, then also the central pipe piece will always be equal to $\lambda/4$ no matter what the working wave. This fact may be utilized for the purpose of obtaining perfectly automatic matching to the cable, even under conditions where the antenna base resistance and the characteristic impedance of the cable differ markedly from each other. To this end the characteristic impedance of the upper pipe piece z_0 is made equal to the antenna base resistance. In other words, at the bottom end 55 the resistance is also z_0 , that is, there is perfect matching for this pipe piece. The characteristic impedance of the bottom pipe piece z_u is made equal to the characteristic impedance of the cable z_k . By means of the central piece of pipe 60 having a length equal to $\lambda/4$, resistance z_0 can be adapted to z_u if the characteristic impedance z_m of the middle pipe piece is chosen in accordance with the known relation $z_m^2 = z_0 z_u$. The characteristic impedance of the middle pipe 65 piece z_m must therefore range between value z_0 and value z_u , and preferably it should be made equal to the geometric mean of the two values. Under this condition, perfectly automatic matching of the antenna to the cable is realized independently of the wave-length.

I claim:

1. A variable length antenna comprising a radiating rod, a tubular member surrounding a portion of said rod and having a counterpoise disc attached to one end, a concentric cable

transmission line having its outer sheath slidably connected to said tubular member and its center conductor connected to said radiating rod.

2. A vertical antenna comprising a radiating rod, a tubular member surrounding a portion of said rod and having a counterpoise disc attached to its upper end, a concentric cable transmission line having its outer sheath slidably connected to said tubular member and its center conductor connected to said radiating rod.

3. A vertical antenna comprising a radiating rod, a tubular member surrounding a portion of said rod and having a counterpoise disc attached to its upper end, a concentric cable transmission line having its outer sheath slidably connected to said tubular member and its center conductor connected to said radiating rod, stay wires supporting said rod in its vertical position and notches in said disc for accommodating said wires.

4. A vertical antenna comprising a radiating rod, a tubular member surrounding a portion of said rod and having a counterpoise disc attached to its upper end, a concentric cable transmission line having its outer sheath slidably connected to said tubular member and its center conductor connected to said radiating rod, and means for shifting said tubular member and the disc attached thereto whereby the free length of said radiating rod may be varied.

5. An antenna system comprising a radiating rod having a length equal to one-quarter of the maximum wave length with which it is desired to operate said antenna, a concentric cable transmission line having a central conductor and an outer sheath, an intermediate conductor having the same length as said radiating rod and interposed between said rod and the central conductor of said transmission line, a tubular member surrounding a portion of said rod adjacent said intermediate conductor, said intermediate conductor and a portion of said transmission line; means for connecting the sheath of said transmission line to said tubular member and a counterpoise disc attached to said tubular member at the end adjacent said radiating rod, said tubular member and counterpoise disc being shiftable longitudinally along said radiating rod whereby the operating wave length may be adjusted.

6. An antenna system comprising a radiating rod having a length equal to one-quarter of the maximum wave length with which it is desired to operate said antenna, a concentric cable transmission line having a central conductor and an outer sheath, an intermediate conductor having the same length as said radiating rod and interposed between said rod and the central conductor of said transmission line, a tubular member surrounding a portion of said rod adjacent said intermediate conductor, said intermediate conductor and a portion of said transmission line, means for connecting the sheath of said transmission line to said tubular member and a counterpoise disc attached to said tubular member at the end adjacent said radiating rod, the diameter of said tubular member at the end adjacent said radiating rod being so chosen with respect to said rod that the impedance of the transmission line formed by said tubular member and the portion of said radiating rod there-within is equal to the radiation resistance of the free portion of said radiating rod, the diameter of said intermediate conductor being so chosen

with respect to the diameter of said tubular member that the impedance of said intermediate conductor is equal to the geometric mean between the radiation resistance of said radiating rod and the impedance of said transmission line and the diameter of the end of said tubular

member remote from said counterpoise disc being so chosen with respect to the diameter of said intermediate member that the characteristic impedance is equal to the impedance of the transmission line.
